P. MILES.

Meat Mincing Machine.

No. 36,229.

Patented Aug. 19, 1862.

Inventor:

Purches Miles

UNITED STATES PATENT OFFICE.

PURCHES MILES, OF NEW HAVEN, CONNECTICUT.

IMPROVED MEAT-MINCING MACHINE.

Specification forming part of Letters Patent No. 36,229, dated August 19, 1862.

To all whom it may concern:

Be it known that I, PURCHES MILES, of the city and county of New Haven, and State of Connecticut, have invented new and useful Improvements in Mincing-Machines; and I do hereby declare that the following is a full, clear, and exact description of the construction and operation of the same, reference being had to the accompany drawings making a part of this specification, in which—

Figure 1 is a perspective view of a machine complete and working. Fig. 2 is a longitudinal section. Fig. 3 is a transverse section, 1 2. Figs. 4 and 5 are sections of one set of cutters enlarged. Fig. 6 is a perspective view of the box. Fig. 7 is a side view of the clamp used to fasten the box to a table.

Same letters refer to like parts.

The nature of my invention consists, first, in the peculiar construction of the cutters, whereby I attain cheapness of construction and increased facility for cleaning after use, as when the machine is open they may be readily removed, cleaned, and reset into the machine for use without extra adjustment, and when the machine is closed for use they are perfectly firm and may be worked with only one set of cutters, or both, as it may be desired to make the mince coarser or finer; secoud, in the construction of the beater-shaft by casting the shaft or arbor, beaters, and forcing-flanges in one piece and forming a groove between each pair of beaters on the shaft for ends of the cutters to rest in for support; third, in the construction and arrangement of a box for a mincer to serve the double purpose of a case to contain the mincer when not in use and to serve as a support for the mincer when in use.

To enable others skilled to make and use my invention, I will proceed to describe its construction and operation.

A is the cylinder, opening through the center, hinged at *a*, and locked together for use, by the clasp *b*. In both the upper and lower parts of the cylinder A are formed recesses B to receive the plate C, containing the cutters D. To make these cutters, or sets of cutters, the steel plates or cutters D are set in the sand before casting, and project into the mold sufficiently that when the metal C is poured in

it will flow onto and unite solidly with the plates or cutters D, as shown in Figs. 4 and 5.

E is the arbor, having a bearing at each end, *c c*, and turned by the crank F.

G are beaters, spirally set and cast on the arbor E, and of one and the same piece.

H H are spiral flanges, also cast on and of the same piece of the arbor E. Between the beaters G, on and around the arbor E, are turned grooves *d*, in which rest the end *e* of the cutters D, so that when the cutters D are in their place and the end *e* in the groove *d* they cannot vibrate, but are firmly held by the grooves *d*, and yet allow the arbor E to revolve freely.

f are spiral ribs around the interior of the cylinder A, or that portion of it occupied by the spiral flanges H H, and which, in combination with the spiral flanges H H, feed the substance to be minced to the beaters and cutters.

I is the hopper into which the substances to be minced are placed, and from thence pass through the machine out, minced, at the opening O. On the upper plate of cutters is cast a pin, P, by which to hold the cutters in their place when in the act of closing the machine.

K is a box, apparently of common construction.

L is the lid.

m are sockets on the side M of the box in which to set the feet *n* of the machine for use.

N is a clamp (*s*, the screw) for holding the box firmly to a table, T. In the side W of the box is made a hole, U, through which to clamp it, if desired.

To operate my mincer, place the box K upon a table, as in Fig. 1, set the machine on the side M of the box K, placing the feet *n* in the sockets *m*, put the substance to be minced into the hopper I, turn the crank F, which will revolve the arbor E, and the spiral flanges H H will draw the substance into the cylinder and, revolving, force it around the cylinder and on the spiral ribs *f* to the spirally-set beaters G, which in their turn force it against and past the cutters D, and by continued feeding will carry it through all the cutters and out at the opening O. If it is desired to make the mince fine, use both sets of cutters; if coarser, take out one set of cutters and

operate as before. To clean the machine, open the cylinder, when the arbor E and the plates C of cutters may be removed for the purpose.

I am aware that cutters for mincers have been united solidly to a metal bar by its being cast thereon, as set forth in the patent of Joshua Bills, March 13, 1860; therefore I do not claim the same as new, but

What I do claim as new and useful, and desire to secure by Letters Patent, is—

The cutters D, united solidly with a metal plate C, by being cast thereon, in combination with the grooves d, in the manner and for the purpose substantially as set forth.

PURCHASES MILES.
